UNITED STATES PATENT OFFICE.

LEOPOLD KOROPP AND VICTOR F. BERGMAN, OF CHICAGO, ILLINOIS.

DESIGN FOR A WREATH.

55,621.

Specification for Design.

Patented July 6, 1920.

Application filed February 4, 1920. Serial No. 356,243. Term of patent 3½ years.

To all whom it may concern:

Be it known that we, LEOPOLD KOROPP and VICTOR F. BERGMAN, citizens of the United States, residing at 4906 North Albany avenue and 617 Cornelia avenue, respectively, in the city of Chicago, county of Cook, and State of Illinois, have invented a new, original, and ornamental Design for a Wreath, of which the following is a specification, reference being had to the accompanying drawing, forming part thereof.

The figure is a front view of the wreath, showing our new design.

We claim:

The ornamental design for a wreath as shown.

LEOPOLD KOROPP.
VICTOR F. BERGMAN.

Witnesses:

WM. E. ANDERSON,
FRED M. DAVIS.
